Patented July 22, 1924.

1,502,137

UNITED STATES PATENT OFFICE.

EARL J. W. DE FOREEST AND FREDRICK W. BAILEY, OF TULSA, OKLAHOMA.

IDENTIFICATION TAG.

Application filed November 7, 1922. Serial No. 599,527.

To all whom it may concern:

Be it known that EARL J. W. DE FOREEST and FREDRICK W. BAILEY, citizens of the United States, residing at Tulsa, in the county of Tulsa and State of Oklahoma, have invented certain new and useful Improvements in Identification Tags, of which the following is a specification.

This invention relates to devices for guarding against the theft of automobiles and other vehicles. Where reliance is placed solely on State registration tags and the ability of one to prove ownership of his automobile through the usual identification means, recovery, in the event of theft, is frequently delayed and much annoyance and inconvenience experienced because of the very inadequate protection afforded by such means of identification. Therefore, it is one of the primary objects of the present invention to provide a combined license, identification certificate, and abstract of title, and a novel means for housing and displaying the same in such a manner as to positively preclude any removal, substitution, alteration, or other disturbance of the displayed identification certificate and license without detection, these several parts constituting a medium whereby the actual owner of the automobile or other vehicle may be identified beyond question, and any unauthorized user of the automobile apprehended with certainty.

The improvements embodying the invention are designed primarily for employment in connection with the tag holder forming the subject-matter of Patent 1,260,156, issued to E. J. W. De Foreest, March 19, 1918, and it is contemplated that the invention be employed under an established and authorized system of registration whereby the authorities issuing the license, identification certificate, and abstract of title, may cooperate with the actual owner of the vehicle in identifying the same in the event of theft, unauthorized use, or disputed possession of the vehicle, in establishing ownership.

The invention contemplates, as previously stated, the employment within the holder disclosed in the said patent, of an instrument constituting a license, an identification certificate, and an abstract of title, and another important object of the invention is to so arrange these component parts and so mount the same within the holder as to preclude alteration, substitution, or tampering

with the license and identification certificate without mutilation or destruction of the same thus rendering it immediately evident that theft or unauthorized use has been attempted, and in this connection the invention has as a further object to provide against any mutilation of the abstract of title so that this medium of identification will remain intact and cannot be disturbed except by the proper authorities.

Another object of the invention is to provide means for the purposes explained above which will also prove useful under other conditions, as for example, where it becomes necessary for the owner of the automobile to be identified, or where it is desired to individually identify various parts of the automobile or the accessories to provide for their ready identification in the event of theft.

In the accompanying drawings:

Figure 1 is a perspective view of the device embodying the invention and the holder within which it is to be mounted, the parts being shown disassembled;

Figure 2 is a detail vertical sectional view through the device with the parts assembled;

Figure 3 is a horizontal sectional view on the line 3—3 of Fig. 2;

Fig. 4 is a perspective view illustrating one of the attaching members for the holder;

Fig. 5 is a plan view of the combined license, identification certificate, and abstract of title, the component parts thereof being spread out;

Fig. 6 is a horizontal sectional view through the device shown in Fig. 5 arranged in one manner for disposal within the holder;

Fig. 7 is a similar view illustrating another manner of arranging the said device.

As the holder for the assemblage of parts comprising the invention is, with minor exceptions to be presently pointed out, identical with the patent above referred to, a brief description of the same will suffice. The holder is best illustrated in Figs. 1, 2 and 3 of the drawings and comprises a back plate 1 having overhanging frame members 2 at its opposite vertical edges and a similar member 3 at its lower edge, these members in connection with the back plate forming a pocket to receive the identification devices embodying the present invention. The upper side of the holder is adapted to be closed by a flange or frame member 4 extending along the upper edge of a plate 5 which is

adapted to be slid downwardly into the holder under conditions to be presently explained and is provided at its lower edge with a rearwardly projecting locking flange 6 designed to ride over and engage beneath locking tongues 7 preferably stamped out from the back plate 1. Also for a purpose to be presently explained the plate 5 is formed with openings 8 designed to be located opposite the said tongues 7 in the locked position of the plate. The holder is designed to be secured to any convenient part of the automobile or other vehicle as, for example, to the back thereof, indicated in the drawings by the numeral 9, and for this purpose attaching clips 10 are employed and each of these clips, as clearly illustrated in Figs. 1 and 4 of the drawings, comprises a small metallic plate bent intermediate its ends and having its portions at the opposite sides of the bend therefore offset, one of these portions being indicated by the numeral 11 and the other by the numeral 12. The portion 11 is designed to be passed through a slot 13 formed in the said back of the automobile body, and the portion 12 will then rest against the inner face of the plate 1. In order to prevent the portion 12 passing through a slot 14 which is formed in the plate 1 to accommodate the bend in the clip 10, it is preferable that this portion 12 be of greater width than the portion 11 and the said bend so as to provide abutment shoulders 15.

The assemblage embodying the invention includes a transparent pane 16 which is preferably of glass although other transparent materials might be employed for the purpose. The assemblage also includes a protective medium for the abstract of title, which medium is indicated by the numeral 17, and preferably comprises a plate 18 of metal of substantially the same dimensions as the pane 16, and for a purpose to be presently explained, formed with openings 19. The identification medium comprises a combined license, identification certificate, and abstract of title, indicated in general by the numeral 20, and consisting of a single sheet 50 of paper or card board having a line of perforations 21 medially between its ends, thus dividing the sheet into two portions, one indicated by the numeral 22 and the other by the numeral 23. In assembling the several parts the portion 22 of the sheet is secured by adhesive to one face of the pane 16, the plate 18 is disposed against the back of this portion of the sheet, and the other portion 23 of the sheet is then folded against the rear side of the said plate, the margins of the pane, the plate, and the two portions 22 and 23 of the identification sheet, being in registration or substantial registration. The assemblage is then disposed against the front face of the plate 5, and the whole is

slid downwardly into the holder 1 until the flange 6 rides over and engages beneath the locking tongues 7 whereupon the parts will be automatically locked and the assemblage embodying the identification medium will be 70 permanently housed within the holder, being marginally engaged on all sides by the frame members 2, 3 and 4 and concealing and preventing access to the locking tongues 7, so long as its component parts remain 75 intact.

The portion 22 of the sheet 20 constitutes a license and a certificate of registration or identification, and therefore bears an appropriate heading legend indicated by the numeral 24. There is also printed upon the face of this portion of the sheet, as indicated by the numeral 25, the name of the State issuing the license. There is also printed as at 26 the number of the license, and as at 27, the year in which issued. In a suitably designated space 28 there is to be mounted a photograph of the owner of the car, and preferably opposite this space there will be printed legends 29 and 30 designating spaces in the first of which the owner is to sign his name, and in the second of which the name of his wife or other equitable owner may be written or signed. Another legend 31 designates a space in 95 which the chauffeur's name may be written or signed. A group of legends 32 may likewise be printed upon the face of the card or sheet and will designate suitable spaces in which will be written, for example, the name of the car, the type, model, engine number, machine number, and horse power. Also upon the face of the sheet there may be written or printed, as at 33, the name of the city or town in which the owner resides, and his street address. The authorities issuing the license will impress their seal of authority, as at 34, and there will preferably be taken, upon the said face of the sheet, for example, in juxtaposition to the seal 34, an imprint 35 of one of the owner's fingers. Preferably the word "Code" is printed upon the face of the card as at 36, and opposite this word there is printed or written an arbitrary code word 37. The code word 37 is, as stated, arbitrarily selected and the significance thereof will presumably be known only to the owner of the car and the authorities issuing the license. For example, in the present instance the word is "Bara" and the translation thereof is "Arab". Other code devices may be agreed upon and, for example, the initials of the owner may be selected for this purpose. The initials of the owner in the example illustrated are "F. W. B.", and the code words chosen may be "Fort Worth Bulletin", these words being registered with the authorities and presumably known only to them and to the owner of the car. By 130

these devices, should it become necessary for the owner of the car to prove his identity to any one, that one could satisfy himself by communicating with the authorities is-
5 suing the license, but one making unauthor-
ized use of the car could not furnish the
requisite proof and would therefore be un-
able to offer a satisfactory explanation as
to his possession of the car. Reference has
10 been made above to the usefulness of the
invention in identifying accessories or parts
if lost or stolen, and this may be accom-
plished by stamping the code word upon
such parts either alone or in combination
15 with the initials of the owner.

The other portion 23 of the sheet 20 con-
stitutes an abstract of title and is design-
ated by a suitable legend indicated by the
numeral 38. Also there are preferably
20 printed upon the face of this portion of the
card or sheet suitable legends 39 designat-
ing spaces in which may be printed or writ-
ten the name of the manufacturer, the name
of the sales agent, or agency, the name and
25 address of the first, second, and subsequent
buyers, as well as the dates on which the
sales transactions took place, and the date
of manufacture. There is also printed a
legend 40 indicating a space in which may
30 be written the name of the owner of the
vehicle, and the sheet may also bear his
address. Furthermore, if desired, a legend
42 may be printed upon the face of the
sheet indicating spaces in which may be
35 written the name and address of any future
purchaser of the machine. As indicated by
the numeral 43, impressions of one or more
of the owner's fingers may be made in a
space left for the purpose upon the face
40 of the said portion of the sheet.

As previously stated the sheet 20 is to
be assembled with the pane 16 and plate 18
by securing the face of the portion 22 of
the said sheet to the face of the pane, dis-
45 posing the plate 18 against the other side
of the said portion 22, and then folding the
portion 23 along the line of perforations 21
to position back of the said plate 18. With
the parts thus assembled and they being in-
50 troduced into the holder and the holder
closed and locked, it will be evident that
access cannot be had to the portion 22 con-
stituting the license and identification cer-
tificate, without breaking the pane of glass
55 16 and mutilating the said portion of the
sheet. However, the plate 18 serves as a
means for protecting the portion 23 of the
sheet which bears the abstract of title, and
the said abstract will remain housed within
60 the holder.

If it is desired to further insure of mutila-
tion of the portion 22 of the sheet in the
event of attempt being made to remove it,
the said portion of the sheet may be ar-
65 ranged between two panes of glass 44 and

45, the first corresponding to the pane 16,
and the other being interposed between the
said portion of the sheet and the plate 18.
In this instance the said portion of the sheet
would be secured, as for example by adhe-
70 sive, to the opposing faces of both panes 44
and 45. In any event the abstract of title
borne upon the portion 23 of the sheet will
be protected from mutilation by the plate 18.

It will be understood that after the identi-
fication medium is inserted within the holder
and the holder is sealed, access cannot be
gained to said medium except by breaking
the glass 16 or the two panes 44 and 45, as
the case may be. Therefore a new identi-
80 fication medium cannot be substituted for an
old one, even by those authorized to make
such substitution except by breaking the
pane or panes and then inserting an instru-
ment through the openings 8 and 11 to 85
spring back the locking tongues 7 and per-
mit of removal of the plate 5.

Having thus described the invention, what
is claimed as new is:

1. The combination with a holder for an 90
identification medium and which holder is
open at its front and adapted to be sealed
against intact removal of the said medium,
of a transparent pane in said holder exposed
at the open front thereof, a protective plate 95
within the holder in rear of the pane, and
an identification medium having a portion
disposed between the pane and plate and
another portion disposed in rear of the plate
and protected thereby.

2. The combination with a holder for an 100
identification medium and which holder is
open at its front and adapted to be sealed
against intact removal of the said medium,
of a transparent pane in said holder ex-
posed at the open front thereof, a protec-
105 tive plate within the holder in rear of the
pane, and an identification medium having a
portion disposed between the pane and plate
and facially united to the pane, and another
portion disposed in rear of the plate and
protected thereby.

3. The combination with a holder for an 110
identification medium and which holder is
open at its front and is adapted to be sealed
against intact removal of the said medium,
of a transparent pane in said holder exposed
at the open front thereof, a protective plate
115 within the holder in rear of the frame, and
an identification medium having a portion
disposed between the pane and plate and
facially united to the pane, and another por-
tion disposed in rear of the plate and pro-
tected thereby.

4. The combination with a holder for an 120
identification medium and which holder is
open at its front and adapted to be sealed
against intact removal of the said medium,
of a transparent pane in said holder ex-
posed at the open front thereof, a protective 125
130

- plate within the holder in rear of the pane, and an identification medium comprising a sheet of material bearing identification indicia and weakened along an intermediate line, the portion at one side of the weakened line being disposed between the pane and plate, and the portion at the other side of the weakened line being disposed in rear of the said plate and protected thereby.
5. The combination with a holder for an identification medium and which holder is open at its front and adapted to be sealed against intact removal of the said medium, of a transparent pane in said holder exposed at the open front thereof, a protective plate within the holder in rear of the pane, and an identification medium comprising a sheet of material bearing identification indicia and weakened along an intermediate line, the portion at one side of the weakened line being disposed between the pane and plate, and the portion at the other side of the weakened line being disposed in rear of the said plate and protected thereby, the 25 said sheet at its weakened line being folded around one edge of the said plate.
6. The combination with a holder for an identification medium and which holder is open at its front and adapted to be sealed against intact removal of the said medium,

of frangible panes in said holder, one exposed at the open front thereof, a protective plate within the holder in rear of the other pane, and an identification medium having a portion disposed between said panes and 35 facially united thereto and another portion disposed in rear of the plate and protected thereby.

7. The combination with a holder for an identification medium comprising a back 40 plate having frame members at three sides, a yieldable locking element carried by the plate, a locking member having a frame portion extending at the other side of the holder and provided with means engageable by the said locking element, of a frangible pane in the holder exposed at the open front thereof, a protective plate within the holder in rear of the pane and provided with an opening, the said locking member being likewise 45 provided with an opening for registration with the opening in the plate and both of said openings being opposite the locking element, and an identification medium having a portion disposed between the pane and 50 plate and facially united to the pane.

In testimony whereof we affix our signatures.

EARL J. W. DE FOREEST. [L. S.]
FREDRICK W. BAILEY. [L. S.]
